APPARATUS FOR GUIDING CABLES

Neil P. Larsen and Herman J. Troche, Cleveland, Ohio, assignors to The American Coach and Body Company, Cleveland, Ohio, a corporation of Ohio

Application May 8, 1937, Serial No. 141,522

5 Claims. (Cl. 254—190)

This invention relates to an apparatus for guiding cables. More particularly, the present invention is concerned with a cable-guiding apparatus, especially adapted for use in connection with cable-winding mechanism carried by trucks and other vehicles. The invention, however, is well adapted for stationary hoisting units. In many commercial fields, automotive trucks are used for construction, maintenance and erection of power lines, gas lines, water conduits, telephone lines, and the like. In these fields it has been found expedient to utilize automotive trucks, which are provided with a power-driven cable winding mechanism. In order that the space within the body of the truck may be advantageously utilized for the transporting of workmen, materials, tools and the like, the hoisting unit is generally located adjacent the forward end of the body. The cable, when in use, extends from the hoist unit to the rear of the truck and then to the article for which this hoist is to be utilized. In many instances, the winches are used for towing loads, drawing cables and other similar tasks, and at times, the article to be drawn or hauled by the winch cannot be aligned with the truck. Therefore, the cable extends angularly from the winch to the article to be drawn, making it difficult to properly reeve the cable on the winding drum, causing premature wear and breakage of the cable, as well as preventing the utilization of a great share of the body space during such time as the winch is in use, often requiring the removal of the contents of the truck body.

The general object of this invention is to provide an improved apparatus for guiding the cable from the load to the winch in such a measure as to overcome the disadvantages above pointed out.

Other objects of our invention will become more apparent from the following description, reference being had to a preferred form of the invention, illustrated in the accompanying drawings. The novel features of the invention will be summarized in the claims.

In the drawings, Fig. 1 is a plan view of a truck, having the improved cable guiding mechanism mounted thereon; Fig. 2 is an enlarged plan view of the cable-guiding mechanism; Fig. 3 is an elevation of the guiding mechanism; Fig. 4 is a substantially vertical section of the guiding mechanism, as indicated by the line 4—4 on Fig. 3; Fig. 5 is a fragmentary horizontal section, the plane of this section being indicated by the line 5—5 on Fig. 4; Fig. 6 is a fragmentary rear ele-

vation, similar to Fig. 3, but illustrating the parts in different positions; Fig. 7 is a fragmentary side elevation and illustrates a mechanism for retaining the cable in contact with the guiding mechanism.

In the drawings, there is generally indicated in Fig. 1 a truck 10, of a type used by public utility corporations in connection with their service and maintenance departments. This truck is provided with a hoisting unit 11, having a winding drum 12 located at the forward end of the storage compartment, or body of the truck. A cable 15 extends directly to the rear of the truck from the drum 12 of the hoisting unit to the improved guiding mechanism 20, and from thence to a load. The guiding mechanism as illustrated is positioned on the floor of the truck adjacent its rearmost end and overhangs the rearmost edge of the truck. This mechanism is so arranged that the cable may extend angularly therefrom in any direction for attachment to a load, which angle may change during the reeving of the cable, and still be properly guided by the guiding mechanism to the winding drum, to enable proper reeving, including level winding of the cable on the drum.

As shown in the drawings, especially Figs. 3, 4, and 5, the improved guide mechanism comprises a pulley or sheave 25, rotatably mounted on a shaft 26. The shaft is mounted in a U-shaped bracket 27, which extends rearwardly from the truck. The shaft is secured against axial movement by any suitable means. The bracket 27 extends upwardly and rearwardly from the sheave to an annular horizontally extending hollow hub formation 28, through which the cable 15 extends, as indicated in Fig. 4.

The hub 28 of the bracket 27 is mounted in a bearing 30, for free rotary movement about a horizontal axis extending parallel with the truck. The hub 28 is provided with a shoulder 31 which seats against one side of a bearing sleeve 32, carried by the bearing 30, while the other end of the hub is threaded as indicated at 32 to receive locking nuts 33 which prevent axial movement of the bracket. The arms 27 of the bracket member 28 are each provided with an outwardly and upwardly extending ear 40. The ears embrace the sides of the sheave and, as will be noted from Fig. 3, form substantially a continuation of the wall 25a of the annular cable receiving recess of the sheave. These ears guide the cable directly to the sheave.

The bearing bracket 30 is secured to the floor of the truck. To this end the bracket is pro-

vided with a horizontally extending flange 36 which engages the floor of the truck, and is also provided with downwardly depending ears, such as those indicated at 37, for engaging the rear-most or end wall of the truck. Suitable bolts 38 extend through the flange 36 and are arranged to secure the bracket to the floor of the truck.

The cable is normally retained in the annular recess of the sheave by a roller 41. This roller is rotatably mounted on a pin 42, carried by a yoke 43, which in turn, is pivotally mounted on the sheave pin 26 as shown in Fig. 5. The pin 42 may be prevented from axial movement in any well-known manner. It will be noted from Fig. 5 that the roller 41 has an outwardly extending annular boss 44 provided with an annular recess 45. This boss is arranged to enter between the flanges 25a of the sheave, and bring the walls of the recess 45 of the roller into close engagement with the cable, thus maintaining the cable in contact with the sheave.

The roller is resiliently maintained in the position illustrated in Figs. 1 to 6 inclusive by a spring 50 which is coiled around a hub-like formation 51, of the yoke 43. One end of the spring extends over a pin 54 carried by the yoke, while the other end of the spring extends loosely through an opening in a lug or boss 55 of the pulley bracket 27.

From the foregoing description, it will be seen that the present invention provides an apparatus for guiding a cable from a winding drum to a load, and insures level winding of the cable on the drum, regardless of the direction of the load from the winding mechanism relative to the longitudinal axis of a truck on which such mechanism is mounted and accomplishes this by maintaining the stretch of the cable which overlies the truck, substantially normal to the axis of the winding mechanism, and parallel with the longitudinal axis of the truck. While the invention is particularly adapted for use in connection with vehicles, it nevertheless is in many instances well adapted for use in stationary hoisting mechanisms.

We claim:

1. In a device of the character described, the combination with a winding drum adapted and arranged to be secured to one end of a platform 50 with its axis extending substantially parallel with said end, a bracket secured to the opposite end of the platform and provided with an annular opening extending in a direction normal to the axis of said drum, a second bracket mounted in 55 said first-named bracket for movement about the axis of the opening therein and having an opening concentric with such axis, said last-named bracket having a pair of ears extending outwardly from said platform, a sheave rotatably supported in said ears for movement about an axis extending normal to the axis of said openings, the periphery of said sheave being substantially tangent to said axis, a pair of arms pivotally mounted to the second-named bracket 60 to swing about the axis of said sheave, a roller carried by said arms and in engagement with a cable extending over the sheave, and resilient means acting on the second named bracket and

arms to normally maintain said roller in a tangential position relative to said sheave.

2. A cable guiding device comprising in combination, a main frame, a sheave frame having a shank rotatably supported in the main frame, the shank being hollow to permit the passage of a cable therethrough, a sheave in said sheave frame for supporting the cable which extends through the shank of the sheave frame, a bracket swivelly mounted on the sheave frame, a roller journalled in the bracket and having a cable engaging groove therein, the groove on the roller being in close proximity to the groove in the sheave whereby the cable is engaged by the roller at all times at its point of tangency to the sheave, and a torsion spring acting against the sheave frame and the bracket for urging the bracket to swing in one direction about the axis of the sheave.

3. A cable guiding device comprising in combination a main frame, a sheave frame having a shank rotatably supported therein, a sheave journalled in the sheave frame, a bracket also journalled on the sheave frame on the same axis as the sheave, a roller journalled in the bracket, the bracket having a hub, a torsion spring surrounding the hub, and having one end thereof attached to the sheave frame and the other end thereof attached to the bracket.

4. A cable guiding device comprising in combination, a main frame, a sheave frame having a shank rotatably supported in the main frame, said shank being hollow to permit the passage of a cable therethrough, a sheave journalled in the sheave frame and having a cable receiving groove therein, a bracket mounted for swinging movement about the axis of the sheave, a roller journalled in the bracket and having a cable engaging portion entering the groove in said sheave and a spring acting upon the sheave frame and the bracket for urging the bracket to swing in one direction with reference to the sheave.

5. In a device as described, a pivotally mounted tubular supporting structure mounted to 45 swivel in a rotatable manner on its axis, a pulley supported on said structure and rotating on an axis at 90 degrees transverse to the axis of the swivel and offset from such axis, the pulley being adapted as a guide lead having a taut cable 50 extending through said tubular structure and over the pulley, the point of contact of a taut cable with the pulley being offset from the axis of the swivelly mounted structure whereby when a taut cable passes over the guide pulley at an 55 angle to the swivel axis and turns in an arc around such swivel axis, the guide pulley follows the motion of the cable and causes a partial rotation of the swivel structure, a pressure means having a pivotal connection to the axle of the 60 guide pulley, and means to urge said pressure means to turn in an arc in the plane of the pulley to position the pressure means substantially at the point of tangency of the cable lead from the guide pulley.
